ATTORNEY.

UNITED STATES PATENT OFFICE.

MARSHALL T. GOWER, OF STOCKTON, CALIFORNIA, ASSIGNOR, BY DIRECT AND MESNE ASSIGNMENTS, OF TWO-THIRDS TO WADE HOLLINGSWORTH, OF STOCKTON, CALIFORNIA, AND ONE-THIRD TO CHARLES W. RALPH, OF LOS ANGELES, CALIFORNIA.

FAUCET.

1,264,293.

Specification of Letters Patent. Patented Apr. 30, 1918.

Application filed May 21, 1917. Serial No. 169,913.

To all whom it may concern:

Be it known that I, MARSHALL T. GOWER, a citizen of the United States, residing at Stockton, in the county of San Joaquin, State of California, have invented certain new and useful Improvements in Faucets; and I do declare the following to be a full, clear, and exact description of the same, reference being had to the accompanying drawings, and to the characters of reference marked thereon, which form a part of this application.

This invention relates to improvements in valved faucets and is particularly designed as a faucet for tanks or receptacles used in the storage and transportation of fluids of all kinds especially gasoline, distillate, and the like. The now commonly used faucets very quickly begin to leak after being in use especially on gasoline and distillate tanks due to the absence of any lubricating qualities in such fluids. The valve seat in such commonly used faucets being of intricate parts it is almost impossible to successfully repair the faucet to prevent the leakage and the result that there is a great deal of waste of the material and also other objectionable features.

In my improved invention I aim not only to produce a valve for the faucets which will be less susceptible to leakage and also one in which when the leakage occurs the seat may be quickly and easily renewed at very little expense.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claim.

In the drawings similar characters of reference indicate corresponding parts in the several views.

Figure 1 is a vertical longitudinal sectional view through the faucet and valve showing the parts disassociated.

Figs. 2 and 3 are views of modified forms of valves which may be used.

Referring now more particularly to the

characters of reference on the drawings the numeral 1 designates the faucet casing turnable in which is the valve stem 2 having an 55 operating handle 3. The operating handle 3 is hinged to the stem 2 as at 4 and is provided with a slot 5 whereby it may be fitted over a lock bar 6 and locked in position by means of a padlock or other suitable means 60 7. This prevents tampering with the contents of the receptacle by an unauthorized person.

My improved valve structure is provided by means of forming an annular recess 8 65 at the head of the faucet 1 and placing therein the removable valve seat 9, such valve seat 9 being of course centrally orificed as is usual. Between the valve seat 9 and the stem 2 the faucet casing 1 is provided with a web 10 movable through which is a pin 11 carrying on its outer end a disk or plate 12. On the stem 2 is an eccentric cam 13 which moves against the disk 12 when the stem 2 is turned to force the pin 7t 11 against the valve plug 14 and open communication through the orifice in the valve seat. The disk 12 of course is of lesser diameter than the orifice to permit of free flow of fluid therethrough. The numeral 15 80 designates an auxiliary casing provided with threads 16 arranged to engage threads 17 in the recess 8. The end of this casing 15 engages the valve seat 9 and holds it in position within the annular recess 8. The 85 opposite end of the casing 15 is threaded as at 18 to fit on to the outlet pipe of the fluid containing receptacle or on any other fitting desired. Within the casing 15 is a caging 19 terminating at its end in a web 20. On 90 the valve plug 14 is a caging 21 terminating in a ring 22 which when the parts are assembled is guided along the caging 19. A spiral spring 23 normally holds the valve plug 14 against the valve seat 9 to keep the 95 faucet closed.

When it is desired to use the faucet, the handle 3 is released and used to turn the stem 2. This action turns the cam 13 into engagement with the disk 12 and moves the 100 pin 11 against the plug 14 and forces it back against the pressure of the spring 23. This opens communication through the orifice in the valve seat 9 into the faucet 1. The fluid

flows through the casing 15 and through cagings 19 and 21 and around the plug 14 and then out through the faucet 1. When the valve stem 2 is turned so as to disengage 5 the cam 13 from engagement with the pin 11 the spring 23 immediately moves the plug 14 to close the orifice in the valve seat. By means of my improved structure the 10 plug and valve seat may be made so as to have a perfectly tight fit with respect to each other which greatly lessens the tendency of the faucet to leak. If leakage should occur either the valve seat or the plug can quickly and easily be renewed at a small 15 expense by merely withdrawing the faucet from the casing 15.

Instead of the valve plug 14 I may use a ball valve 24 as shown in Fig. 2 but would still have a removable valve seat 9^a. Or I 20 may use instead of the valve structure herein described an independent tubular member 25 which would be held in position within the annular recess 8 and would be provided at its outer end with a valve plug 26 25 which would have thereon a pin 27 projecting to a point adjacent the cam 13. The valve would be normally held closed by means of a spring 28 interposed between the web 29 within the member 25 and a pin 30 30 on the pin 27. This spring would normally

hold the valve plug closed and then when the cam 13 engaged the pin 27 it would open the valve. This structure could likewise be easily renewed if leakage occurred.

From the foregoing description it will be 35 readily seen that I have produced such a device as substantially fulfills the object of the invention as set forth herein.

While this specification sets forth in detail the present and preferred construction 40 of the device, still in practice such deviations from such detail may be resorted to as do not form a departure from the spirit of the invention as defined by the appended claim. 45

Having thus described my invention what I claim as new and useful and desire to secure by Letters Patent is:

A faucet comprising a casing provided with a removable valve seat, a spring pressed 50 valve plug normally held against the seat, a guide web immediately adjacent the valve seat, a pin guided through the web and engaging the plug, a valve stem, a cam on the stem engageable with the pin to move the 55 plug away from the seat, the spring pressed plug normally holding the pin in engagement with the cam.

In testimony whereof I affix my signature.

MARSHALL T. GOWER.
